UNITED STATES PATENT OFFICE

92,132

DESIGN FOR A ROOF OR SIDING

Richard A. Holdsworth, Bayside, N. Y., assignor
to The Barrett Company, New York, N. Y., a
corporation of New Jersey

Application April 10, 1933, Serial No. 47,745

Term of patent 14 years

To all whom it may concern:

Be it known that I, RICHARD A. HOLDSWORTH, a citizen of the United States, residing at Bayside, county of Queens, State of New York, have invented a new, original, and ornamental Design for a Roof or Siding, of which the following is a specification, reference being had to the accompanying drawing, forming part hereof,

Fig. 1 is a plan view of a fragmentary portion of the roof shown in Fig. 2.

Fig. 2 is a plan view of a portion of a roof or siding embodying this invention.

I claim:

The ornamental design for a roof or siding substantially as shown.

RICHARD A. HOLDSWORTH.
